ATTORNEY

UNITED STATES PATENT OFFICE

HAROLD L. PULVER, OF NORTH ATTLEBORO, MASSACHUSETTS

ORNAMENTAL BEAD CHAIN

Application filed April 26, 1932. Serial No. 607,568.

My invention relates to improvements in bead chains of a type adapted to form bracelets, necklaces and the like for ornamental purposes.

5 While my invention may be applied to any type of bead it is particularly adapted to be used on a so-called type of button bead, which has hitherto been mounted in the usual mounting prior to stringing on a chain or 10 other type of string. In place of the usual mounting I carefully select beads which preferably have oppositely disposed flat portions on the surface thereof and provide string holes therein. I then string this type of bead 15 on a string without any mountings at all and as a substitute for said mountings, I employ flat discs strung on said string means between each bead, abutting the oppositely disposed flat portions of adjacent beads and being al- 20 ternately inclined relative to each other. By employing these discs and stringing them on the string means intermediate of the beads, the discs appear to form a mounting for each 25 individual bead and I am enabled to provide an attractive type of bead string. When the string is pulled tightly the discs take a shape obliquely behind each bead to give a simulation of an individual mounting therefor.

30 A further object of my invention is to provide a novel method of stringing beads of a general type of button beads having polygonal facets thereon or oppositely disposed flat portions thereon and making mountings therefor by the simple expedient of stringing 35 discs intermediate the beads.

These and such other objects of my invention as may hereinafter appear will be best understood from a description of an embodiment thereof such as is shown in the accom- 40 panying drawing.

In the drawing, Fig. 1 is a front elevation of a bead chain constructed in accordance with my invention with the chain in curved position.

45 Fig. 2 is a side elevation of the same with the string in a straight position.

Fig. 3 is a sectional view with the bead chain disposed in the position shown in Fig. 2.

50 In the drawing, wherein like characters of reference indicate like parts throughout, 10

generally indicates a bead chain constructed in accordance with my invention.

My invention is particularly adapted to provide a novel method of stringing so-called button beads having polygonal facets without providing individual mountings therefor on the chain or without providing a solid mounting having individual bead holes therein. However, any type of bead may be employed and I employ the word "bead" to broadly include not only glass or semi-precious beads or buttons, but also if desired precious or other types of stones or ornaments, which may be mounted similarly to beads. The beads are provided in the embodiment shown with a flat top and bottom portion 12 and 14 respectively and the flat polygonal facet portions 16 extending upwards from the median line 18 thereof and the similar complementary flat polygonal facet portions 20 extending downwardly from the median line thereof and the string holes 22 extending diametrically thereof below the median line thereof. While my invention is primarily adapted for stringing beads of this type, it is obvious that for the purpose of my invention that the beads may only need to have oppositely disposed flat portions such as two oppositely disposed individual lower facets 20^a and 20^b on the lower surface thereof and the remainder of the beads being round or of any other shape desired. To form the beads 11 into the bead string 10, I preferably employ the string means 24 extending through

said string holes 22. While any type of a string may be employed, I preferably as shown employ the flexible chain 24. As the improved mounting means 26 for the individual beads 11, I preferably provide the flat disc shaped members 26 strung on said string means between each bead, each abutting an alternate flat facet portion 16 and 20 respectively on adjacent beads and being alternately inclined relative to said beads to form the outwardly flaring mounting portion 28 shown in Fig. 1, giving a simulation of an outwardly flaring mounting on each side of each respective bead. Said disc members 26 are provided with a preferably central

hole 30 for receiving the flexible string means 24.

In the preferred embodiment shown I preferably only employ the diametrically oppositely disposed facets or flat portions 20^a and 20^b on each bead extending downwardly from the median line thereof and I so diametrically locate the string holes that they extend diametrically thereof below the median line 18 10 thereof and I then arrange the beads in a line so that alternate beads will face upwardly and downwardly and as each bead is reversed to face alternately upwardly and downwardly it is then obvious that the disc members 15 will abut oppositely disposed lower flat facet portions of alternate beads below the median line thereof and that the other parts of the beads may be round or of any other desired shape.

20 It is thus apparent that I have provided a novel mounting for beads or other types of stones of this general type having oppositely disposed flat facet portions diametrically opposite thereon, preferably below the median line thereof and string holes therein preferably below the median line thereof, and mountings for said stones, jewels or beads comprising flat discs strung on a flexible string means between each bead, each flaring 25 outwardly so as to simulate a mounting built right into the string structure itself and which when the string is extended will compactly fit against the facet portions to compactly hold the entire bead string together, 30 of a pleasing appearance, relatively cheap to manufacture and relatively easy to construct.

It is understood that my invention is not limited to the specific embodiment shown and 40 that various deviations may be made therefrom without departing from the spirit and scope of the appended claims.

What I claim is:

1. A bead chain comprising beads having 45 flat tops and bottoms and flat polygonal facet portions extending upwards from the median line thereof and similar complementary polygonal facet portions extending downwardly from the median line thereof and 50 string holes extending diametrically thereof below the median line thereof, arranged in a line so that alternate beads will face upwardly and downwardly respectively, disc shaped members having a substantially central hole herein abutting opposed flat facet portions of alternate beads and being alternately obliquely inclined relative to said beads and string means extending through 55 said disc holes and bead holes to string them together.

60 2. A bead chain comprising beads having flat polygonal facet portions extending upwards from the median line thereof and similar complementary polygonal facet portions 65 extending downwardly from the median line

thereof and string holes extending diametrically thereof below the median line thereof, arranged in a line so that alternate beads will face upwardly and downwardly respectively, disc shaped members having a substantially central hole therein abutting the flat facet portions of alternate beads and being alternately obliquely inclined relative to said beads and string means extending through said disc holes and bead holes to string them together.

70 3. A bead chain comprising beads having flat polygonal facet portions extending downwardly from the median line thereof and string holes extending diametrically thereof below the median line thereof, arranged in a line so that alternate beads will face upwardly and downwardly respectively, disc shaped members having a substantially central hole therein abutting the flat portions of alternate beads and being alternately obliquely inclined relative to said beads and string means extending through said disc holes and bead holes to string them together.

75 4. A bead chain comprising beads having diametric flat portions extending downwardly from the median line thereof and string holes extending diametrically thereof below the median line thereof arranged in a line so that alternate beads will face upwardly and downwardly respectively, disc shaped members having a hole therein abutting the flat portions of alternate beads and being alternately obliquely inclined relative to said beads and string means extending through said disc holes and bead holes to string them together.

80 5. A bead chain comprising beads having string holes and oppositely disposed flat portions on the surface thereof, string means for said beads extending through said string holes and mountings for said beads comprising flat discs strung on said string means between each bead abutting the oppositely disposed flat portions of adjacent beads and being alternately inclined relative to each other.

85 6. A bead chain comprising beads having string holes and flat portions on the surface thereof, string means for said beads extending through said string holes and mountings for said beads comprising flat discs strung on said string means between each bead abutting flat portions of adjacent beads and being alternately inclined relative to each other.

90 In testimony whereof I affix my signature.
HAROLD L. PULVER.
